UNITED STATES PATENT OFFICE.

GUSTAVE F. ERHARD, OF SCRANTON, PENNSYLVANIA, ASSIGNOR TO THE SCRANTON LACE COMPANY, OF SCRANTON, PENNSYLVANIA, A CORPORATION OF PENNSYLVANIA.

DESIGN FOR A TEXTILE FABRIC.

Application filed July 19, 1928 Serial No. 27,583. Term of patent 7 years.

To all whom it may concern:

Be it known that I, GUSTAVE F. ERHARD, a citizen of the United States, residing at Scranton, in the county of Lackawanna and State of Pennsylvania, have invented a new, original, and ornamental Design for Textile Fabrics, of which the following is a specification, reference being had to the accompanying drawing, forming part thereof.

The figure is a plan view of a textile fabric, showing my new design. In the reproduction of the design in cloth, the portion of the

design represented in the figure as being unshaded and symmetrically disposed in respect to the shaded portion appears the same as that portion of the design which is shaded in the figure.

I claim:

The ornamental design for a textile fabric, substantially as shown and described.

In testimony whereof I hereto affix my signature.

GUSTAVE F. ERHARD.
